UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

COAL CUTTING MACHINE

Application filed November 30, 1928. Serial No. 322,887.

The present invention relates to certain new and useful improvements in coal cutting machines of the type having an elongated cutter arm equipped with a cutter chain adapted to engage the coal to cut it when the cutter arm is presented edgewise to the body of the vein.

It is the especial object of this invention to provide, in a machine of the class described, improved mechanism for the actuation of the cutter chain having great strength, durability and efficiency, and of the vertical dimensions suitable for use in extremely thin veins of coal.

A further object is to combine, in a machine such as above described, convenient and efficient means for the transmission of power from the motor of the mining machine to the wheels of a truck adapted for the transportation of the machine from one working place to another.

The means whereby I attain these objects are fully set forth in the following specification and illustrated in the accompanying drawing of which

Fig. 1 is a general plan view of a coal cutting machine of the class to which my present invention relates.

Fig. 2 is a sectional view taken along the line II—II of Fig. 1.

Fig. 3 is a sectional view taken along the line III—III of Fig. 1.

Like numerals refer to similar parts in the several figures.

In Fig. 1 of the drawing I have shown a machine of the well known shortwall type having a main frame 1 adapted to rest upon and slide in any direction over the floor of a mine. Mounted upon the frame 1 are two winding drums 2 and 3, upon which are windable the feeding and guiding ropes 4 and 5, respectively. The ropes 4 and 5 are adapted to be attached to suitably positioned anchoring devices external of the machine, and the drums 2 and 3 are provided with suitable actuating and controlling mechanism where-

by suitable draft may be applied to said ropes to move and guide the machine relative to the material to be mined in the manner which is well understood in the mining machine art.

The main frame 1 constitutes the magnetic field frame of an electric motor having a longitudinally disposed armature shaft 5, whereby the several elements of the machine are actuated. Means is provided for the supply and control of the electric current for the actuation of said motor, but such devices are well understood in the art and their illustration and description is not thought to be required at this time.

The main frame 1 comprises a sole plate 13, upon which the machine is adapted to rest and be moved over the floor of a mine. The main frame also comprises a horizontal integral web 13' spaced somewhat above sole plate 13, and between web 13' and an upwardly offset portion of sole plate 13 is secured a cutter frame 6. Guideways are formed along the lateral edges of the cutter frame, and in them travels a cutter chain 7 of the well known type having renewable cutter bits 8 adapted to engage a coal body to cut a kerf therein.

The cutter chain 7 passes around and is actuated by a sprocket wheel 9, which is keyed to the lower end of a vertical shaft 10. The shaft 10 is journaled at its lower end in a sleeve bearing 11 formed integrally with web 13'. Shaft 10 is positioned in bearing 11 by means of an annular flange 12, which bears upon the upper face of the bearing so as to support the shaft with its lower end in proximity to the upper surface of the sole plate. In order that the vertical dimensions of the machine may be reduced without the impairment of the strength and efficiency of the parts, the sleeve 11 is given a considerable downward extent so as to insure ample bearing surfaces for the shaft 10. As here shown, the lower edge of the bearing extends somewhat below the medial horizontal plane of

the cutter bar. To bring the rim of sprocket wheel 9 into proper relation with the cutter bar the sprocket is of dished conformation, its hub 14 being keyed to the lower end of shaft 10 and its rim surrounding the lower end of the bearing and lying in the proper medial horizontal planes of the cutter bar. By this construction the entire length of hub 14 is below the lowermost plane of the sprocket rim. The upper end of shaft 10 is received in a bearing cap 15, which is journaled in the hub 16' of a bevel gear wheel 20. The hub 16' is concentrically arranged within the hub 16 of a further bevel gear 17, this latter hub being journaled in a bearing 18 of the machine frame. Gear wheels 20 and 17 are secured together in the construction illustrated, but they can, of course, be made integral.

The bevel gear 17 is engaged by a bevel pinion 19 fixed to the forward end of the armature shaft 5'. The bevel gear 20 has formed on its lower surface clutch teeth 21 adapted to cooperate with similar teeth on the clutch member 22, which is splined to shaft 10. A suitable shifting mechanism is provided whereby the clutch member 22 may be moved upwardly into engagement with the teeth 21 to drive the shaft 10 and actuate the cutter chain 7, or it may be moved downwardly out of such engagement to permit the chain to remain idle.

Formed in the frame casting is an oil reservoir 23 from which leads an oil duct 24 communicating with the annular groove 25 formed in the hub 16 of the bevel gear 17. An oil duct 26 extending from the groove 25 through the metal of the hubs 16 and 16' establishes the passage for oil between the oil reservoir 23 and the reservoir or cavity 27 in the hub 16' above the end of shaft 10, thereby insuring a supply of lubricant for the bearing surfaces 15 and 16.

Journaled in bearings 28 and 29 of the main frame is a horizontally extending shaft 30 to the inner end of which is fixed a bevel gear 31 which meshes with the bevel gear 20. The shaft 30 is held against longitudinal movement by the engagement of the hub 32 and the mutilated collar 33 with the ends of the bearings 28 and 29 respectively. The mutilated collar 33 is formed integral with the shaft 30 and is shaped to provide clutch jaws 34 adapted to engage corresponding jaws formed on the end of a sleeve 35. The sleeve 35 is rotatably and slidably mounted on the shaft 30 outside of the bearing 29, and is provided with two spaced apart annular grooves 36 and 37 adapted to engage the end of a detent pin 38 whereby said sleeve may be held in clutch engaged position or in disengaged position. Formed on the outer end of the sleeve 35 is a sprocket wheel 39 adapted to engage a suitable driving chain not shown in the drawing. These parts are so propor-

tioned and arranged that when the mining machine is loaded upon the truck for transportation from one working place to another, the sprocket wheel 39 will be in suitable position to be connected with other sprocket wheels upon the truck whereby power from the mining machine motor may be applied to the axles of the truck to propel it along the track of the mine in the manner which is well understood in the mining machine art.

By the arrangement of parts above described, I have provided improved power transmission mechanism for the actuation of the cutter chain of a mining machine such as above described, having great strength, durability and efficiency, and of reduced vertical dimensions suitable for use in extremely thin veins of coal, combined with convenient and efficient mechanism for the transmission of power to the propelling mechanism of a truck adapted to transport said mining machine from one working place to another.

What I claim is:

1. In a mining machine of the class described, the combination with a main frame, of a motor mounted thereon, a gear wheel operatively connected with said motor and having a cylindrical hub rotatably mounted in a journal bearing of said frame, a shaft rotatably mounted in a journal bearing within said hub, means to operatively connect said gear with said shaft, an oil reservoir formed in said frame adjacent said journal bearing and having an oil duct communicating with an annular groove in said hub, and an oil duct extending through the metal of said hub from said annular groove to the bearing within said hub as and for the purpose set forth.

2. In a mining machine, a frame of relatively small over-all height, a bottom plate on which the frame is adapted to be supported for movement over the floor of a mine, a horizontal uniplanar web portion integral with the frame and spaced above said bottom plate, a cutter bar secured beneath said web portion and with the top surface of the cutter bar against the lower surface of said web portion, cutter bits circulatory about said bar to cut a horizontal kerf substantially at floor level, a vertical sleeve bearing integral with said web portion to the rear of said cutter bar, the lower end of said sleeve bearing extending below the medial horizontal plane of said cutter bar, a shaft journaled in said bearing and extending below the lower extremity of the latter, and a dished sprocket wheel having its hub secured to the lower end of said shaft and its rim surrounding the lower end of said bearing and lying in medial horizontal planes of the cutter bar.

3. In a mining machine, a frame, a vertical shaft having its upper end disposed in a

bearing formed in said frame, and a gear having a hub journaled in said bearing about the upper end of the shaft, and rotatable relative to the latter, the hub projecting above the end of the shaft to form a lubricant-receiving cavity.

4. In a mining machine, a frame, a vertical shaft having its upper end disposed in a bearing formed in said frame, a gear having a hub journaled in said bearing about the upper end of the shaft, and rotatable relative to the latter, the hub projecting above the end of the shaft to form a lubricant-receiving cavity, the periphery of the hub within the bearing being annularly grooved, a duct communicating the groove with the cavity, and a lubricant reservoir in communication with said groove.

5. In a mining machine, a frame of relatively small over-all height, a bottom plate on which the frame is adapted to be supported for movement over the floor of a mine, a horizontal uniplanar web portion integral with the frame and spaced above said bottom plate, a cutter bar secured between said web portion and an upwardly offset portion of said bottom plate, a vertical sleeve bearing integral with said web portion to the rear of said cutter bar, the lower end of said sleeve bearing extending below the medial horizontal plane of said cutter bar, a shaft journaled in said bearing and extending below the lower extremity of the latter, a dished sprocket wheel having its hub secured to the lower end of said shaft and its rim surrounding the lower end of said bearing and lying in medial horizontal planes of the cutter bar, a downwardly faced beveled gear concentric with the upper end of said shaft, a clutch means comprising a member slidable on said shaft between said gear and sleeve bearing, and a motor disposed within the upper and lower limits of the main frame and having a horizontally extending armature shaft provided with a pinion engaging said gear.

6. In a mining machine, a frame of relatively small overall height, a bottom plate on which the frame is adapted to be supported for movement over the floor of the mine, a horizontal uni-planar web portion integral with the frame and spaced above said bottom plate, a cutter bar disposed between said web portion and an upwardly off-set portion of said bottom plate with the top surface of the cutter bar against the lower surface of said web portion, means for securing the bar in position comprising bolts passed through the web portion, the cutter bar, and the upwardly off-set portion of the bottom plate, the lower extremities of the bolts being above the bottom surface of said plate, cutter bits circulatory about said bar to cut a horizontal kerf substantially at floor level, a vertical sleeve bearing integral with said web portion

to the rear of said cutter bar, the lower end of said sleeve bearing extending below the medial horizontal plane of said cutter bar, a shaft journaled in said bearing and extending below the lower extremity of the latter, and a dished sprocket wheel having its hub secured to the lower end of said shaft and its rim surrounding the lower end of said bearing and lying in medial horizontal planes of the cutter bar.

In testimony whereof I have hereunto set my hand.

NILS D. LEVIN.
